UNITED STATES PATENT OFFICE.

PHILIP H. SANGER, OF ONAWAY, MICHIGAN, ASSIGNOR TO R. M. WALTON,
OF ONAWAY, MICHIGAN.

PLUMB AND SPIRIT LEVEL.

SPECIFICATION forming part of Letters Patent No. 783,897, dated February 28, 1905.

Application filed July 1, 1904. Serial No. 214,888.

To all whom it may concern:

Be it known that I, PHILIP H. SANGER, a citizen of the United States, residing at Onaway, in the county of Presque Isle and State of Michigan, have invented certain new and useful Improvements in Plumb and Spirit Levels; and I do declare the following to be a full, clear, and exact description of the invention, such as will enable others skilled in the art to which it appertains to make and use the same:

This invention relates to a combined plumb and level.

The object of the invention is to provide a tool of this character whereby different levels may be quickly ascertained or determined and the bubble-glasses accurately and conveniently adjusted.

With this and other objects in view the invention consists of certain novel features of construction, combination, and arrangement of parts, as will be hereinafter more fully described, and particularly pointed out in the appended claim.

In the accompanying drawings, Figure 1 is a perspective view of a plumb and level embodying my invention. Fig. 2 is a longitudinal section of the same. Fig. 3 is a cross-section on the plane of one of the sight-screws.

1 denotes the stock of the tool, which, in accordance with my invention, is provided with a longitudinal bore or sight-passage 2, at the ends of which are arranged sight devices 3, said devices consisting of transverse screws fitted in screw-threaded holes 4, from which they may be conveniently removed to enable the bore or passage 2 to be swabbed by a suitable cleaner when choked by dust or other foreign substances. By looking through the bore 2 the operator after setting the tool in the position forming the basis of the leveling may level up one piece of work with another or find different relative levels in a convenient manner, as will be readily understood.

5 is the level-glass, and 6 the plumb-glass. The level-glass 5 occupies a recess 7 in the upper edge of the stock 1 and is exposed at the sight-orifice 8. The recess 7 is closed by a plate 9, suitably secured by screws or other suitable fastenings 10. The plate 9 is pro-

vided with the usual observation-slot 11 and has depending therefrom near one end of said slot a lug or boss 12, to one end of which the glass 5 is pivotally connected, as shown at 13. The opposite end of the glass is supported by a spring 14, fitted upon a stem 15, and is beveled, as shown at 16. A set-screw 17 is mounted in the stock 1 and engages this beveled end 16, whereby the glass is held against the pressure of said spring. By slackening or tightening up this screw the glass 5 may be adjusted in an obvious manner with convenience and nicety to bring the bubble opposite its indicating-mark and held in adjusted position.

The plumb-glass 6 is similarly mounted, being mounted in a plate or frame 18, arranged in a transverse opening 19 in the stock, said frame being pivoted at one (its upper) end, as indicated at 19, and having its opposite or lower end pressed in one direction by a spring 20. Opposite said spring 20 the said lower end of the frame 18 is beveled, as shown at 21, said beveled portion being engaged by a set-screw 22, carried by a plate 23, set within a recess 24 in the lower edge of the stock and secured by screws 25. This plate 25 is provided with a stem or lug 26, guiding and holding the spring 20. It will be seen that this construction enables the plumb-glass 6 to be adjusted and held in a similar manner to the glass 5.

Owing to the construction of the open or skeleton-like stock and the manner of mounting the plumb and level glasses therein the plumb-glass can be seen from either side and at an elevation above or below the instrument, while the level-glass may be seen from either side above the instrument, thus allowing the user to plumb above his head without the use of a step-ladder or other means of elevation and to level any surface slightly below his line of vision.

From the foregoing description, taken in connection with the accompanying drawings, the construction and operation of the invention will be readily understood without requiring a more extended explanation.

Various changes in the form, proportion, and the minor details of construction may be

resorted to without departing from the principle or sacrificing any of the advantages of this invention.

Having thus described my invention, what I claim as new, and desire to secure by Letters Patent, is—

The herein-described level and plumb, comprising a longitudinally - grooved skeleton stock having a central vertical opening, a plumb-glass pivoted at its upper end in said opening, a set-screw for adjusting its lower end, a level-glass above the plumb-glass, means

for adjusting said glass, a longitudinal sight-bore in the stock, and threaded sight-pieces intersecting the sight - bore and removably mounted therein, essentially as described.

In testimony whereof I have hereunto set my hand in presence of two subscribing witnesses.

PHILIP H. SANGER.

Witnesses:

S. S. TOWER,
R. MAY WALTON.
